UNITED STATES PATENT OFFICE

100,190

DESIGN FOR A CUP OR SIMILAR ARTICLE

Jack G. Allen, Chicago, Ill., assignor to F. H. Noble & Co., Chicago, Ill., a corporation of Illinois

Application May 13, 1936, Serial No. 62,614

Term of patent 7 years

To all whom it may concern:

Be it known that I, Jack G. Allen, a citizen of the United States, residing at Chicago, in the county of Cook, State of Illinois, have invented a new, original, and ornamental Design for a Cup or Similar Article, of which the following is a specification, reference being had to the accompanying drawing, forming a part thereof.

In the drawing, Figure 1 is a side elevation of a cup or similar article showing my new design;

Figs. 2 and 3 are similar side elevations of the same, at angles approximately 40° and 80° from the position shown in Fig. 1; and

Fig. 4 is a perspective view of said cup.

I claim:

The ornamental design for a cup or similar article, as shown.

JACK G. ALLEN.
